(57) **CLAIM**

The ornamental design for a bag as shown and described.

DESCRIPTION

FIG. 1 is a first perspective view of a bag in a first configuration, showing the new design.

FIG. 2 is a second perspective view of the bag in the first configuration;

FIG. 3 is a rear elevation view of the bag in the first configuration;

FIG. 4 is a top plan view of the bag in the first configuration;

FIG. 5 is a front elevation view of the bag in the first configuration;

FIG. 6 is a bottom plan view of the bag in the first configuration;

FIG. 7 is a left side elevation view of the bag in the first configuration, the right side elevation view being a mirror image of the left side elevation view;

FIG. 8 is a perspective view of the bag in a second configuration;

FIG. 9 is a left side elevation view of the bag in the second configuration, the right side elevation view being a mirror image of the left side elevation view;

FIG. 10 is a front elevation view of the bag in the second configuration;

FIG. 11 is a rear elevation view of the bag in the second configuration;

FIG. 12 is a top plan view of the bag in the second configuration; and,

FIG. 13 is a bottom plan view of the bag in the second configuration.

The short dash broken lines depict stitching that forms no part of the claimed design. The long dash broken lines depict portions of the bag that form no part of the claimed design.

1 Claim, 10 Drawing Sheets
